TWIN HYDRAULIC JACK ASSEMBLY

Lowell C. Weinberg, Redondo Beach, Calif.

Application July 31, 1951, Serial No. 239,604

6 Claims. (Cl. 254—89)

(Granted under Title 35, U. S. Code (1952), sec. 266)

The present invention relates generally to hydraulic jacks and specifically to a twin hydraulic jack for use with wheels and tires of aircraft.

In the servicing of aircraft in hangars or on flight decks extreme difficulty has attended the replacement of wheels or tires due to the compact construction of wheel hubs and axles used with retractable landing gear. The hubs and axles are necessarily set close to the rim of the wheels and with the large size tires now in use on aircraft it has been found difficult to locate a vertically lifting device beneath the axle stub. The large size tires when partially or totally deflated spread out beneath the wheel to a degree which prohibits the use of a hydraulic jack beneath the jacking point on the hub or axle.

The present invention has for its object to provide a hydraulic lifting device which permits vertical lift of an aircraft wheel despite the collapsed and spread out tire carcass.

Another object of the invention is to provide a hydraulic jack having an extremely low compressed height and a high-extended height.

A further object of the invention is to provide a hydraulic jack that is readily portable and has wheels which without adjusting or latching to inoperative position do not bear any of the lift load while the jack is in position.

A further object of the invention is to provide a hydraulic jack of inexpensive construction and one capable of lifting large loads as found aboard aircraft carriers.

These and other objects of the invention will be more clearly understood by reference to the accompanying description and drawings in which:

Fig. 1 shows a partially exploded plan view of the invention.

Fig. 2 shows a cross-sectional view taken on line 2—2 of Fig. 3.

Fig. 3 shows a top plan view, and

Fig. 4 shows a side view in elevation of the assembled invention.

Referring more particularly to the drawing in which like numerals indicate like parts throughout the several views, in Fig. 1, will be seen a pair of hydraulic jacks 10 having bases 11 secured to bar 12 by angle brackets 13 and 14 (as seen in Fig. 4) at each end of bar 12. Brackets 15 and 16 on bar 12 support a pump 17 which is connected at its outlet end 18 with the distributing valve 19 and at its input end 21 to the oil reservoir 22 by pipe 23. The distributing valve 19 is connected by conduits 24 and 25 to each of the bases 11 by means of connectors indicated at 20.

Bolted to bases 11 are brackets 26 having axles 27 and wheels 28 rotatable thereon.

The hydraulic jacks 10, as shown in Fig. 2, are constructed of outer sleeves 30 screw threaded into the bases 11, inner sleeves 31, and pistons 32, and are extended slidably together by fluid pumped into chambers 33 in the bases 11. As shown in the partially exploded view in Fig. 1 and also in the cross-section view of Fig.

2

2, the assembled sleeves 30, 31, and pistons 32 of each jack fit loosely into the caps 35 at each end of the beam 36.

Caps 35 are cylindrical in shape and have their inner ends 37 concave to match and to provide a continuous bearing surface for the convex ends 38 of pistons 32 under conditions of flexing of beam 36 or while one jack 33 in the bases 11. As shown in the partially exploded is extended slightly higher than the other.

10 Slidable on beam 36 are two riders 39 and 40, each having depending flanges 41 to prevent them from sliding sideways from beam 36. Rider 39 is a relatively low plate with a hole 42 into which fits pin 43 formed in the base of the load cup 44. Other load cups 45, 46, with 15 identical pins 43, are of different thicknesses and are replaceable with cup 44 in rider 39 or may be used with rider 40 in the hole 48 on top of the adjusting screw 47. Beam 36 has hole 49 at its center for receiving one of 20 pins 43 when one of the cups 44, 45, or 46 are used to bear the weight of the lifted load without the increment of height added by the use of either rider 39 or 40.

Each of the riders 39 and 40 have identical spring-based centering pins 51 having the pull-handles 52, the 25 pin 51 of the rider chosen for use coacting with hole 53 in beam 36 to fix the rider in the center of the beam. Load cups 44, 45, 46 have short cables 54 securing them against loss or misplacement.

The purpose of riders 39 and 40 and load cups 44, 45 and 46 is to provide means for contacting and bearing the 30 lifted load at minimum jack travel regardless of the height of the lifting points of the load from ground level. The height of the lifting point will determine which bearing means is to be used in order that the full vertical jack travel remains and is present to lift the load the required 35 distance. At the lowest lifting point, hole 49 and its load cup is utilized; at an intermediate height rider 39 is used, and at higher lifting points, rider 40 with its adjusting screw 47 is used. Load cups 44, 45 and 46 are interchangeable with each other in holes 42, 48, and 49 40 and have different sized depressions 63 to fit different sized loading points.

In operation, the oil return valve 60 is closed and 45 distributing valve handle 61 is centered to obtain equal flow from pump 17 to each jack 10, and air vent 62 in the top of the reservoir 22 is opened to replenish the oil in pump 17 as it fills the jacks. If one jack 10 raises faster than the other or if it is desirable to have one 50 jack higher than the other to accommodate slight irregularities in the deck surface, handle 61 is moved towards the jack requiring the more oil, the particular construction of the valve 19 permitting the distribution of oil to either or both jacks at will. Depending upon the distance, deck and the loading point of the axle or hub, either of riders 39, or 40, with any one of the loading 55 cups 44, 45, 46 may be used, and the adjusting screw 47 may be used with rider 40 to obtain the greatest amount of lift in each case.

The low compressed height of the beam and its relatively high extended height make it possible to raise the 60 wheels of most aircrafts for easy and speedy wheel or tire removal. The construction of the jacks with their particularly tight oil seals and O rings 65 permit high loading of the hydraulic jack without leakage or failure. The outer sleeve 30 is undercut at its end beyond threads 65 64 and base 11 is formed with an annular channel 66 to provide space for an O ring 67, preventing leaks between bases 11 and outer sleeves 30.

Referring to Fig. 3, bracket 26 has an open space 68 70 between the two arms 69 of the bracket 26. This space 68 is provided for the purpose of permitting the fingers of the operator's hand to pass through when taking a firm hold of the axle 27. It is then possible for the operator,

having a firm hold on the grip axle, to lift that end of the jack assembly in an upwards motion until the pair of wheels 28 on the opposite end of the jack assembly are in contact with the ground or other supporting surface, and both jack bases 11 are entirely clear of the ground or said supporting surface. The operator can now move the jack assembly to any desired location, simply by pushing or pulling, since the one end of the jack assembly is supported by the pair of wheels 28 at one end and the other end is supported by the firm grip of the operator's hand on the axle 27.

The operator can lift either end of the jack assembly thus permitting the placing of the jack under either the right or left hand landing gear of an aircraft from the forward end of the aircraft, and have the lifting beam 36 of the jack assembly next to the aircraft wheel. Upon lowering of the jack off of the wheels, bases 11 provide a substantially immovable or fixed supporting means.

It should be understood, of course, that the foregoing disclosure relates to only a preferred embodiment of the invention and that numerous modifications or alterations may be made therein without departing from the spirit and the scope of the invention as set forth in the appended claims.

The invention described herein may be manufactured and used by or for the Government of the United States of America for governmental purposes without the payment of any royalties thereon or therefor.

What is claimed is:

1. A readily portable hydraulic lifting assembly having a low height and a high lift comprising a pair of hydraulic jacks rigidly secured together in spaced relation by a single straight bar; a base positioned on the lower surface of each of said jacks; a single hydraulic pump mounted on said bar and operatively connected to each of said jacks; a load transmitting cap surmounting each of said jacks; and a single load receiving beam extending between said caps and rigidly secured thereto.

2. A readily portable hydraulic lifting assembly comprising a pair of hydraulic jacks in spaced relation; a base attached to the lower surface of each of said jacks; a single straight bar extending between and rigidly secured to said bases at points spaced above the lower surfaces thereof; a single hydraulic pump mounted on said bar and operatively connected to each of said jacks; a load transmitting cap surmounting each of said jacks; and a single load receiving beam extending between said caps and rigidly secured thereto.

3. A manually portable lifting assembly comprising a pair of hydraulic jacks in spaced relation; a base positioned on the lower surface of each of said jacks; a single straight bar extending between and rigidly secured to said bases at points spaced above the lower surfaces thereof; means for operating said jacks mounted on said bar and operatively connected to each of the jacks, said

means comprising a single pump, a hydraulic fluid supply and a single valve for simultaneously controlling the amount of fluid flow to each jack; a load transmitting cap surmounting each of said jacks; a single load receiving beam extending between said caps and rigidly secured thereto.

4. A manually portable lifting assembly comprising a pair of hydraulic jacks in spaced relation; a base positioned on the lower surface of each of said jacks; a single straight bar extending between and rigidly secured to said bases at points spaced above the lower surfaces thereof; means for operating said jacks mounted on said bar and operatively connected to each of said jacks; a load transmitting cap removably fitted over each of said jacks; a single load receiving beam extending between said caps and rigidly secured thereto; a series of loading point receiving means of graduated heights movably mounted on said beam.

5. A manually portable hydraulic lifting assembly comprising a pair of hydraulic jacks in spaced relation, each of said jacks having a curved load bearing surface; a base positioned on the lower surface of each of said jacks; a single straight bar extending between and rigidly secured to said bases at points spaced above the lower surfaces thereof; means for operating said jacks mounted on said bar and operatively connected to each of the jacks; a load transmitting cap removably fitted over each of said jacks, the lower bearing face of each cap resting on the curved load bearing surface of the jack and having a matching configuration; and a single load receiving beam extending between said caps and rigidly secured thereto.

6. A manually portable lifting assembly comprising a pair of hydraulic jacks in spaced relation; a base positioned on the lower surface of each of said jacks; a single straight bar extending between and rigidly secured to said bases at points spaced above the lower surfaces thereof; means for operating said jacks mounted on said bar and operatively connected to each of the jacks; and a load transmitting cap removably fitted over each of said jacks; a single load receiving beam extending between said caps and rigidly secured thereto.
